UNITED STATES PATENT OFFICE.

JAMES SPARROW, OF READING, ENGLAND.

RAILWAY.

SPECIFICATION forming part of Letters Patent No. 656,753, dated August 28, 1900.

Application filed July 11, 1899. Serial No. 723,436. (No model.)

To all whom it may concern:

Be it known that I, JAMES SPARROW, a subject of the Queen of Great Britain, residing at Reading, in the county of Berks, England, have 5 invented certain new and useful Improvements in Railways, of which the following is a full and complete specification, such as will enable those skilled in the art to which it app pertains to make and use the same.

10 This invention relates to railways; and the object thereof is to provide means whereby a double-track railway may be merged into a single-track railway without the employment of movable switches.

15 According to my invention cars may be moved from a double track and thence onto a single track in crowded thoroughfares or in crossing bridges, and may again be moved onto a double track, so as to freely pass each 20 other.

Another feature of my invention consists in its applicability to single tracks and single-road-bed railways in which turnouts may be instituted which the cars may enter and leave 25 in passing one another without the assistance of movable switches. These results are obtained by the construction and arrangement of tracks, all as hereinafter set forth.

My invention is fully disclosed in the following specification, of which the accompanying drawings form a part, in which like reference characters denote like parts in the several views, and in which—

Figure 1 is a plan view of a section of a railway provided with tracks constructed and arranged according to my invention; and Figs. 2 and 3 are enlarged cross-sections of the railway-rails which I employ, Fig. 2 being a section of Fig. 1 on the line 3 3 and Fig. 3 a section of Fig. 1 on line 5 5.

Referring more particularly to the drawings, I provide two parallel rails A and B for a single road-bed, the rail A being provided with longitudinal grooves *a* and *b* and longitudinal operative bearing-shoulders *c*, *d*, and *e* and the rail B with longitudinal grooves *f* and *g* and longitudinal operative bearing-shoulders *h*, *j*, and *k*. The grooves *a*, *b*, *f*, and *g* are adapted to receive the flanges of 45 the wheels and the bearing-shoulders *c*, *d*, *h*, and *j* the rims thereof. The bearing-shoulders *e* and *k* are designed as guards.

At the points C and D of the rails A and B where the road-bed broadens to form a double-track switch or turnout the central shoulders 55 *d* and *j* of the rails A and B are split to form two diverging rails consisting of the extension of projection of each of the rails A and B, as shown at E, F, G, and H, E and F being the extensions of the rail A and G and H the extensions of the rail B, as shown in Fig. 1. The rails E and F diverge at the same angle as the rails G and H, the rail E extending parallel with the rail G and the rail F with the rail H.

At the points C and D where the rails A 65 and B respectively divide, as above described, said rails are thickened, as shown in Fig. 1. The rails E, F, G, and H are provided, respectively, with a central longitudinal groove *a'*, *b'*, *f'*, and *g'*, which are respectively unbroken continuations of the grooves *a* and *b* in the rail A and the grooves *f* and *g* in the rail B.

At either side of the groove *a'* the rail E is provided with a longitudinal operative bearing-shoulder *c'* and *d'*, which are unbroken continuations, respectively, of the shoulders *c* and *d* of the rail A. The rails F, G, and H are provided, respectively, at either side of their respective central longitudinal grooves 75 *b'*, *f'*, and *g'* with longitudinal operative bearing-shoulders *d*² and *e'*, *k'* and *j*², and *j'* and *h*', which are respectively unbroken continuations of the longitudinal shoulders *d* and *e*, *k* and *j*, and *j* and *h* of the respective rails 80 A and B. The rails F and G cross at K, the central groove *f'* and shoulders *d*² and *e'* of the rails E and the central groove *f'* and shoulders *k*' and *j*² of the rail G still retaining their identity, the shoulders *d*² and *e'* being split to allow of the continuous formation 85 of the grooves *f'* and *d*² uniting at L and the shoulders *e'* and *j*² uniting at M. The tracks E, F, G, and H again curve, respectively, at N, O, P, and Q, and thence extend parallel, 90 as in the case of a double track.

The operation and use of the rails constructed and arranged as described are as follows: Suppose a car to be mounted upon each of the sets of the rails E and G and F and H. The flanges of the wheels of the car mounted upon the rails E and G would operate within the grooves *a'* and *f'*, and the rims of the said 95 wheels would bear upon the shoulders *j*² and *c'*.

The flanges of the wheels of the car mounted upon the tracks F and H would operate within the grooves b' and g' , and the rims of said wheels would bear upon the shoulders d^2 and h^2 . If now either car desired to enter upon the single tracks A and B, it would move forward, and upon said tracks A and B the operation of the wheels of the car mounted upon the rails E and G would be as follows: Arriving at 10 the crossing-point K of the rails F and G the wheel-flanges operating within the groove f' of the rail G would cross the groove b' of the rail F and the corresponding wheel-rims would cross the break in the shoulder j^2 of the rail G 15 at the crossing of the grooves b' and f' of the respective rails F and G and would continue on upon the said shoulder j^2 . Coming to the point D the wheel-rims riding upon the shoulder j^2 of the rail G would pass upon the 20 central bearing-shoulder j of the rail B, and the wheel-flanges operating within the groove f' would enter the groove f in the rail B. Similarly the wheel-flanges operating within the groove a' of the rail E on coming to the 25 point C would enter the groove a in the rail A, and the wheel-rim riding upon the shoulder d' of the rail E would pass upon the shoulder c of the rail A, and the grooves a' and f' of the corresponding rails E and G being continuations of the grooves a and f of the 30 respective rails A and B. This passage of the wheels from the rails E and G to the rails A and B would be accomplished without the aid of any movable switch. In corresponding 35 manner the wheels of the car mounted upon the rails F and H would pass upon the rails A and B, the grooves b' and g' , respectively,

thereof being continuations of the grooves b and g of the rails A and B, respectively, and the shoulders d^2 and h of the rails F and H being, respectively, continuations of the shoulders d and h of the rails A and B. On the respective rails E, G, F, and H the shoulders d' , h' , e' , and j' serve as guards, as do the flanges e and k of the respective rails 45 A and B.

It is evident that my invention is susceptible to many changes in the construction and arrangement of the rails above described, and I claim all such as come within the spirit 50 of my invention.

Having fully described my invention, I claim as new and desire to secure by Letters Patent—

A railway-rail provided with two parallel 55 longitudinal grooves and three longitudinal operative bearing-shoulders arranged respectively at either side of an intermediate said grooves, the said intermediate shoulder being provided with a pair of divergent extensions 6c constituting secondary bearing-shoulders springing from the end thereof, and the other bearing-shoulders being extended and curved to parallel each the next adjacent secondary bearing-shoulder, substantially as 65 shown and described.

In testimony that I claim the foregoing as my invention I have signed my name, in presence of the subscribing witnesses, this 29th day of June, 1899.

JAMES SPARROW.
